CLAIM

The ornamental design for a perfume bottle with closure, as shown and described.

DESCRIPTION

FIG. 1 is a perspective view of a perfume bottle with closure showing my new design;

FIG. 2 is a front elevation thereof, the rear elevation being identical thereto;

FIG. 3 is a side elevation thereof, the opposite side being identical thereto;

FIG. 4 is a top plan view thereof; and

FIG. 5 is a bottom plan view thereof.

The neck of the bottle and the closure are made of opaque material; the remainder of the bottle is of transparent material.
